(57) **CLAIM**

The ornamental design for a syringe, as shown and described.

DESCRIPTION

FIG. 1 is a front left top perspective view of a syringe showing the claimed design;

FIG. 2 is a front elevational view thereof, the rear elevational view is a mirror image thereof;

FIG. 3 is a right side elevational view thereof, the left side elevational view is a mirror image thereof;

FIG. 4 is a top plan view thereof; and,

FIG. 5 is a bottom plan view thereof.

The equal length broken lines depict portions of the syringe and form no part of the claimed design. The dot-dash broken lines define the bounds of the claimed design. All broken lines form no part of the claimed design.

1 Claim, 3 Drawing Sheets
